UNITED STATES PATENT OFFICE.

JOHN M. HANSEN, OF PITTSBURG, PENNSYLVANIA.

PEDESTAL-TRUCK.

SPECIFICATION forming part of Letters Patent No. 752,290, dated February 16, 1904.

Application filed November 2, 1903. Serial No. 179,543. (No model.)

To all whom it may concern:

Be it known that I, JOHN M. HANSEN, a resident of Pittsburgh, in the county of Allegheny and State of Pennsylvania, have invented a new and useful Improvement in Pedestal-Trucks; and I do hereby declare the following to be a full, clear, and exact description thereof.

My invention relates to railway-car trucks, and more especially to those known as "pedestal-trucks."

The object of my invention is to so construct a truck of this type as to utilize ordinary standard rolled shapes as far as possible.

Another object of my invention is to provide a pedestal-truck whose side frame is composed of an ordinary rolled flanged beam having plain square ends, together with a pedestal of wrought-steel applied to the ends of said beam.

20 In the accompanying drawings, Figure 1 is a side view of one end of a truck side frame constructed according to my invention. Fig. 2 is an end view of the same. Fig. 3 is a plan view of the same. Fig. 4 is a section on the line 4-4, Fig. 1, and Fig. 5 is a plan view of the pedestal reinforcing-bar.

My improved pedestal side frame is composed of an ordinary rolled flanged beam, such as the channel-beam 1 shown. This has its 30 ends cut off substantially square, as shown, and has attached to each end a pedestal composed of forged or rolled steel, preferably of a flanged bar, such as the T-bar 2, bent into U shape to form the pedestal-jaws and with the leg 3 of the T-bar projecting outwardly and the flanges 4 and 5 projecting laterally. One leg of this U-shaped pedestal is riveted to the flat face of the channel-beam 1, and the 35 outwardly-projecting flange on the opposite leg is preferably sheared off, as indicated at 6. To reinforce this pedestal, I provide a flanged bar, preferably an angle-bar 7, bent into approximately hook shape and having one flange riveted to the upwardly-projecting leg of the T-bar 2 at the top of the pedestal and to the 40 web of the channel-beam 1. The other flange of this angle-bar projects laterally, as shown. A further reinforcement is furnished by means 45 of a plate 9, riveted to the laterally-project-

ing flange of the reinforcing-bar 7 and to the 50 top flange of the channel-beam 1. The reinforcing-bar 7 is slightly bent, as indicated at 10, so as to fit closely against the web of the channel-beam 1.

The lower ends of the pedestal-jaws are 55 closed by means of the spacing-piece 10^a and are tied together by the usual pedestal-bolt 11, having the washers 12. The vertical legs of the T-bar forming the pedestal-jaws are trimmed off at their lower ends in such a way 60 that they will enter into slots formed in the washers 12, as indicated at 13, thus preventing them from turning when the nuts are tightened up.

The side frames of the truck may be connected by means of any suitable transoms, 65 only one such transom being shown, and composed of a channel-beam 14, connected to the side channel-beam 1 by means of an angle-piece 15 and a top connecting-plate 16. 70

It is obvious that various modifications may be made in the design of the truck side frame shown. For instance, instead of a T-bar 2, such as shown, either one or two angle-bars might be used. Furthermore, the reinforcing-plate 9 may be omitted in case the angle-bar 7 is chosen of sufficiently large section to be stiff enough by itself. 75

It will be observed that the truck side frame shown omits the usual heavy and unreliable 80 castings usually employed in this type of trucks and that it is built up almost entirely of ordinary standard sections, which can be readily obtained in the market. Furthermore, the design is such that the rolled sections used are 85 cut off practically square, thus avoiding notching, shearing, and otherwise cutting the same away and very largely reducing the amount of scrap, the only exception to this being at the lower ends of the pedestal-jaws, which are 90 shaped off diagonally, and also the outer jaw, which has the outwardly-projecting leg of the T-bar slightly sheared off to lighten the same.

What I claim is—

1. A side frame for railway-trucks, comprising a rolled flanged beam cut off or fashioned square at its end, and a wrought-metal pedestal of substantially U shape having one 95

- 2
- leg thereof riveted to the end of said beam and provided with a laterally-projecting flange surrounding the axle-box opening.
2. A side frame for railway-trucks, comprising a rolled flanged beam cut off or fashioned square at its ends, and a pedestal comprising a flanged bar bent into U shape and having one leg thereof riveted to the end of said beam and provided with a laterally-projecting flange surrounding the axle-box opening.
3. A side frame for railway-trucks, comprising a rolled flanged beam having its ends cut off or fashioned square, and a pedestal comprising a rolled flanged bar bent into U shape and having an outwardly-projecting flange or leg riveted to the end of said beam, and having a laterally-projecting flange surrounding the axle-box opening.
4. A side frame for railway-trucks comprising a rolled flanged beam cut off or fashioned square at its ends, and a pedestal comprising a T-bar bent into U shape with its leg projecting outwardly, said leg having one jaw riveted to the end of said beam.
5. A side frame for railway-trucks, comprising a rolled flanged beam cut off or fashioned square at its ends, a wrought-metal pedestal of U shape having one leg secured to the end of said beam, and a reinforcing member secured to the upper portion of said pedestal and to said beam.
6. A side frame for railway-trucks, comprising a rolled flanged beam cut off or fashioned square at its ends, a U-shaped forged-steel pedestal having an outwardly-projecting flange riveted to said beam, and a reinforcing-bar riveted to the top of said pedestal and to the side of said beam.
7. A side frame for railway-trucks comprising a rolled flanged beam having its ends cut off or fashioned square, a pedestal comprising a flanged bar bent into U shape secured to the end of said beam, and a reinforcing member comprising a flanged bar riveted to the top of said pedestal and thence extending down diagonally and riveted to the web of said beam.
8. A side frame for railway-trucks, comprising a rolled flanged beam cut off or fashioned square at its ends, a pedestal comprising a flanged bar bent into U shape and having a flange or web projecting outwardly and riveted to the end of said beam, and a reinforcing member comprising a flanged bar having one flange arranged vertically and riveted to the outwardly-projecting flange of said pedestal and to the web of said beam and the other flange projecting laterally.
9. A side frame for railway-trucks, comprising a rolled channel-beam having its ends cut off or fashioned square, a pedestal comprising a flanged bar bent into U shape and having a flange or leg projecting outwardly and riveted to the flat face of said channel-beam, and a reinforcing member comprising a flanged beam having a vertical flange riveted to the outwardly-projecting flange at the top of the pedestal and to the flat face of the channel-beam.
10. A side frame for railway-trucks, comprising a flanged beam having its ends cut off or fashioned square, a U-shaped wrought-steel pedestal having one leg riveted to the end of said beam, a reinforcing-bar secured to the top of said pedestal and extending diagonally downwardly and secured to the web of said beam, and a reinforcing-plate riveted to said reinforcing-bar and the top flange of said beam.
11. A pedestal for railway-trucks comprising a U-shaped member having an outwardly-projecting flange, the lower ends of which are diagonal, a pedestal-bolt extending through the lower ends of the jaws of said U-shaped member, and washers for said bolt provided with slots arranged to receive the lower ends of the outwardly-projecting flange.

In testimony whereof I, the said JOHN M. HANSEN, have hereunto set my hand.

JOHN M. HANSEN.
